UNITED STATES PATENT OFFICE

157,258

COMBINATION SUEDE BRUSH AND CONTAINER THEREFOR

Ira Hertzberg, Yonkers, N. Y., assignor to H. Hertzberg & Son, Inc., New York, N. Y., a corporation of New York

Application December 14, 1948, Serial No. 150,158

Term of patent 7 years

(Cl. D9—2)

To all whom it may concern:

Be it known that I, Ira Hertzberg, a citizen of the United States, residing at Yonkers, in the county of Westchester and State of New York, have invented a new, original, and ornamental Design for a Combination Suede Brush and Container Therefor, of which the following is a specification, reference being had to the accompanying drawing, forming part thereof.

In the drawing

Fig. 1 is a perspective view of a combination suede brush and container therefor, showing my new design in closed position;

Fig. 2 is a perspective view thereof in open position; and

Fig. 3 is a top plan view of the brush portion.

I claim:

The ornamental design for a combination suede brush and container therefor, substantially as shown.
